UNITED STATES PATENT OFFICE

HENRY H. GILBERT, OF DETROIT, MICHIGAN, ASSIGNOR TO GENERAL MOTORS CORPORATION, OF DETROIT, MICHIGAN, A CORPORATION OF DELAWARE

LUBRICATION

Application filed September 28, 1927. Serial No. 222,535.

This invention relates to automotive vehicles and particularly to the oiling system of the internal combustion engine thereof.

In the past some difficulty has been experienced in starting internal combustion engines during cold weather, and it is the object of the present invention to overcome this difficulty by providing a system of lubrication which will permit of an adequate supply of hot oil to be furnished the working parts of the engine during the starting period.

The object of the invention is accomplished by placing at any suitable point near the engine, but preferably in the oil pan thereof, a suitable container through which the oil is forced by the usual oil pump before reaching the bearings. This container is heat insulated by providing a surrounding shell spaced therefrom. This space may be either an air space or may be filled with a suitable insulating material, such as asbestos.

While the engine is running the oil is forced through the container, and in due time becomes heated up and after the engine has stopped the container serves as a reservoir and traps a considerable quantity of hot oil. On restarting the engine this hot oil is forced directly to the bearings or to the cylinders and permits of a ready starting of the engine.

While the disclosure on the accompanying drawings shows the hot oil supplied only to the bearings, an additional lead pipe may obviously be run to each cylinder so that a suitable supply of hot oil may be furnished during the starting period. To prevent a continual supply of the lubricant passing to the cylinders, a thermostatically operated valve may be placed in the pipe and which will be closed after the engine has run a suitable period, due to the generation of heat.

The invention is disclosed on the accompanying drawings in which:

Figure 1 is an end view of a V-type internal combustion engine with parts broken away and portions shown in section to illustrate the invention.

Figure 2 is the detail side view of the container and its connections shown in Figure 1.

Figure 3 is the transverse section through the container on the line 3—3 of Figure 2.

Figure 4 is a view similar to Figure 3 of a modification.

Referring to the numbered parts on the drawings, 10 indicates an internal combustion engine as a whole, 12 one of the cylinders 55 thereof, and 14 the piston operating in the cylinder head.

The engine is equipped with the usual gear type oil pump shown at 16. This pump has an outlet 18 which delivers the oil to a conduit 20 leading to a container 22 resting on the bottom of the oil pan 24, secured to the crankcase 26. The container 22 is so placed that the oil will flow thereto by gravity when the engine is not running. The container 60 22 is heat insulated from its surroundings by means of an outer shell 28. Between the container 22 and the shell 28 there is an air space 30 as shown in Figures 2 and 3. This space may be filled with any suitable heat insulating material 32, such as asbestos, as shown in Figure 4.

The container 22 has an outlet 34 leading to a manifold 36, the branches 38 of which lead to the crankshaft bearings. If desired 75 additional branches may lead to the camshaft bearings.

If desired the outlet 34 may have an additional conduit leading to a groove 40 in the engine cylinder to permit of the conduction 80 of the hot oil to the cylinders during starting periods. In this conduit there will preferably be placed a thermostatically controlled valve which will close when the temperature of the engine reaches a sufficient degree. The 85 object of this valve is to prevent a constant flow of lubricant to the cylinders after the engine is running.

The operation of the construction is as follows:

When the engine is running the pump 16 will force all of the oil into the container 22, and on to the bearing portions of the engine. As the engine continues to run the oil will become heated, and the container 22 will eventually be filled with a supply of hot lubricant. After the engine has stopped, the working parts become cold and during the winter months, some difficulty is experienced in 95 starting the engine. The hot oil trapped in 100

the container 22 will retain its heat for a considerable period, say three or four hours, and on restarting the engine, a few revolutions of the pump will force the supply of hot lubricant held in the container 22 to the bearing or working parts and cause a ready flow of lubricant to the friction surface. This supply of hot lubricant will permit of the ready starting of the engine.

10 I claim:

1. In an oiling system for internal combustion engines having an oil pan and an oil pump, an oil container in said pan for storing heated oil during normal running of the engine, a shell surrounding said container and spaced therefrom to form a heat insulator, a conduit leading from the pump to said container, and a second conduit leading from said container to the working parts of the engine.

20 2. In combination with an internal combustion engine having an oil pan and an oil pump, a container in said pan for receiving and storing heated oil from the pump during normal running of the engine, an insulation around said container, and means for delivering oil from the container to the working parts of the engine during the starting period.

30 3. In combination with an internal combustion engine having an oil pump and an oil pan, a shell resting in the oil pan, a container within said shell and heat insulated therefrom and adapted to store heated oil during the normal running of the engine, an inlet conduit to said container from said pump, and an outlet conduit from said container leading to the engine bearings.

40 4. In a lubricating system for internal combustion engines having an oil pan, an oil pump in said system, a lubricant container in said pan for storing heated lubricant during normal operation of the engine, a conduit leading from the pump to the container, and a second conduit leading from the container to the working parts of the engine to supply heated lubricant when starting the engine.

50 5. In combination with an internal combustion engine having an oil pan and an oil pump, a container in the pan for receiving and storing heated oil from the pump during normal operation of the engine, an insulation comprising an outer shell around said container heat insulated therefrom, and means for delivering oil from the container to the working parts of the engine.

60 6. In combination with an internal combustion engine having an oil pan and an oil pump, a container in the pan for receiving and storing heated oil from the pump during normal operation of the engine, an insulation comprising an outer shell around said container spaced therefrom and confining an air space therebetween, and means for de-

livering oil from the container to the working parts of the engine.

7. In combination with an internal combustion engine having an oil pan and an oil pump, a container for receiving and storing heated oil from the pump during normal operation of the engine, said container immersed in the oil in the oil pan of the engine, an insulation around said container, and means for delivering oil from the container to the working parts of the engine.

8. In combination with an internal combustion engine, a heat insulated container for storing a quantity of hot oil while the engine is running, and means for delivering said stored hot oil to the bearing parts when starting the engine.

9. In combination with an internal combustion engine, means for storing a quantity of hot oil while the engine is running, and a manifold leading to the engine bearings for delivering said stored hot oil to the bearing parts when starting the engine.

10. In a lubricating system for internal combustion engines having an oil pan, an oil pump in said system, a lubricant container in said pan for retaining heated lubricant, a shell surrounding said container and spaced therefrom, a conduit leading from the pump to the container, and a second conduit leading from the container to the working parts of the engine to supply heated lubricant when starting the engine.

11. In a lubricating system for internal combustion engines having an oil pan, an oil pump in said system, a lubricant container in said pan for retaining heated lubricant, means for insulating said container from said oil pan, a conduit leading from the pump to the container, and a second conduit leading from the container to the working parts of the engine to supply heated lubricant when starting the engine.

In testimony whereof I affix my signature.

HENRY H. GILBERT.
